FUEL ECONOMIZING SYSTEM AND APPARATUS

George J. Byrne, Chicago, Ill., assignor to Byrnes Hot Draft Corporation, a corporation of Illinois

Application July 12, 1939, Serial No. 283,943

11 Claims. (Cl. 110—49)

This invention relates to smoke eliminating and fuel economizing systems and apparatus primarily adapted for steam boiler furnaces and the like and, more particularly, to apparatuses applicable to and a system or method for operation of steam boiler or other furnaces with which steam may be generated for any purpose, whereby a fuel such as soft coal including cheap or poor grades thereof may be burned more efficiently and completely and with less loss through smoke and unburned gases than under other or similar conditions of operation without the application of the invention thereto. In certain aspects the invention may be considered as supplemental to or an improvement upon the invention disclosed in my prior Patent 2,183,184 dated December 12, 1939.

The primary object of the invention, of course, is to provide an apparatus and a system or method for the more efficient combustion of soft coal including poor grades thereof and for the reduction if not the complete elimination of smoke and incompletely burned gases and the losses incurred therethrough and, to such ends, other and more specific objects including:

The provision of means for recycling or returning a substantial portion of the exhaust products going to the furnace stack, particularly during initial periods of operation of the furnace, to the fire after mixing such returned combustion products with fresh air and steam;

The provision of a positive or forced feed of fresh air for mixing with combustible parts of furnace exhaust products rather than to rely upon a gravity or merely induced flow of air for such purposes;

The provision of an arrangement of apparatus whereby the particles of combustible material and combustible gases carried in the exhaust products from a furnace are thoroughly commingled and brought into intimate and combustible association with an amount of oxygen sufficient to effect complete combustion thereof;

The provision of means to pre-heat the fresh air used to effect combustion of the combustible parts of the smoke or exhaust products from the furnace, since it would appear that preheating the air accelerates or aids in obtaining an intimate or close contact between the smoke particles and the oxygen of the air mixed therewith;

The provision of a system of automatic control over the supply of air, steam and exhaust products being mixed and fed to the intake draft side of the furnace;

The provision of safety means to prevent the flow of exhaust products from escaping into the 55

furnace room, the same means also being adapted to shut off some or all of the furnace draft when, for instance, the fire is to be banked; and

The provision of an efficient and relatively inexpensive apparatus of the character mentioned and the provision of various novel features in addition to those above generally mentioned, for the attainment of the foregoing and other objects as will become apparent after reading the following description and claims alone or when taken in conjunction with the accompanying drawings in which:

Fig. 1 is a schematic illustration of one embodiment of the invention as applied to a steam boiler furnace the view being in side elevation.

Fig. 2 is also a schematic view, in front elevation of the furnace, boiler and apparatus of Fig. 1.

Fig. 3 is a diagrammatic illustration of the electrical control system utilized in operating the apparatus shown in Figs. 1 and 2 and,

Figs. 4 and 5, respectively, are transverse and longitudinal sectional views of fragments of the mixing or agitating chamber within which the 25 furnace exhaust products or portions thereof are intimately mixed or homogenized and contacted by and with steam and fresh air.

In Figs. 1 and 2 a furnace 2 equipped with a boiler as indicated by the legend on Fig. 1, has a 30 draft intake 3 into the ash pit below the furnace grates (not shown). A fire door through which the fuel is charged into the fire is designated 4 and a pair of doors 5 for access to the boiler or boiler tubes for cleaning and other purposes are 35 designated 5. The boiler may be provided with the usual steam pressure gauge 6, water level gauge (not shown) and with such other accessories as may be useful or desirable, as will be understood. The exhaust gases from the furnace pass into the furnace breeching (not shown) and thence through the exhaust pipe or exhaust stack 7 and thence into the chimney or smoke stack 8 through which they pass to the atmosphere.

45 Suitably hinged as at 9 to be projected to varying extents (through pre-adjustment) into and across the path of products of combustion passing from the furnace and up the smoke stack 8, is a damper or valve 11 to which at 12, is pivoted 50 an operating rod 13 in turn pivoted at 14 to one arm of 15 of a bell-crank lever which is pivoted at 16 and has its other arm 17 connected through a pin and slot connection with an extension 18 of the core (not shown) of a solenoid 19. The solenoid 19 may be supported on brackets 21 at-

tached to a flue or duct 22 which opens into the chimney 8, the operating rod and bell-crank lever being disposed within the duct 22. It may be noted here that when the solenoid 19 is energized the core will be pulled into the coil thereby rotating the bell-crank lever in a clockwise direction which in turn will project the damper or valve 11 into the smoke stack or chimney to deflect products of combustion into the duct 22, the arrangement being such that the valve does not completely close off the chimney flow. Of course through various well known means of adjustment or otherwise the extent of projection of the valve 11 into the chimney flue may be controlled so as to increase or decrease the quantity of products of combustion deflected into the duct 22. When the solenoid is deenergized a spring (not shown) and gravity or gravity alone may serve to close the valve 11 over the end of duct 22.

Products of combustion may flow through the duct 22 into a pipe or duct 23 which leads to a mixing or agitating chamber 24 within which combustible particles and combustible gases contained in the furnace exhaust products are intimately and homogeneously intermingled and contacted with steam and fresh air. After being mixed with steam and fresh air in chamber 24 the products of combustion are drawn from the chamber through a duct 25 by a blower 26 driven by an electric motor 27 and are discharged through a duct 28 into the draft intake side of the furnace, i. e., through the ash pit or beneath the grate, in any suitable manner.

Disposed in the duct 28 is a valve or damper 29 which may be hinged at 31 and pivotally connected with one end of an operating link 32 the other end of which is pivotally connected to an operating arm 33 carried by an extension 34 of a core of a solenoid 35 which may be carried on a bracket 36 secured to the duct 28. The arrangement is such that when the solenoid 25 is energized the valve 29 is moved to the position shown in the dotted lines and when deenergized a spring or other means effects movement of the valve 29 to a position transversely of the duct 28 thereby to close the same.

Leading from the boiler is a steam line 37 in which a solenoid operated valve 38 is disposed and which is connected with a steam header 39 which may run substantially the full length of the mixing chamber 24. Leading from the header 39 are a plurality of pipes or tubes 41 which are carried through and terminate inside of the walls of the mixing chamber 24, as more clearly represented in Figs. 4 and 5, terminating a short distance within the mixing chamber inside of what may be termed nozzle members 42 which may be secured by welding or otherwise in apertures formed in the walls in the mixing chamber and through which apertures the steam jet pipes are projected. Suitable plugs close the apertures. It will be noted that the nozzle members 42 are inclined inwardly and toward the direction of flow of the products of combustion into and through the mixing chamber and similarly the inner ends of the steam jet pipes 41 are inclined in conformity therewith but terminate short of the inner ends of the nozzle members. It will also be noted that there are a plurality of these nozzles and steam jets disposed longitudinally and circumferentially of the mixing chamber at suitably spaced places from one another in each direction. The number and arrangement of nozzles and jets may be varied as circumstances may dictate but should

be sufficient to provide a thorough mixing or homogenizing of air and steam with the products of combustion flowing through the chamber. The amount of steam and air needed may be adjusted in accordance with the rate of flow of products of combustion through the chamber, the character of the products of combustion and other factors as will be understood.

Also disposed within each of the nozzle members 42 is a tube or jet 43 which is adapted to supply a jet of compressed air with the steam into the mixing chamber 24. The several jet tubes 43 are connected to a header or tank 44 which is arranged in close proximity to or against the wall of the mixing chamber and similarly in close proximity to or against the steam header 39 thereby to pre-heat the air being supplied to the chamber 24 substantially to equalize the temperature of the air with the temperature of the exhaust products flowing through the chamber. The tank may be equipped with a pressure gauge 45, if desired, and receives compressed air through pipe 46 from a compressor 47 driven by an electric motor 48. A housing 49 of suitable construction and arrangement to permit accessibility to the mixing chamber, may be placed around the steam header, the air tank, the blower and its motor, and the compressor and its motor, to keep these parts of the apparatus clean and free from dust and dirt.

In Fig. 3 a diagram of the electrical control system is illustrated and reference will now be made to this control system. Wires 51 and 52 leading from a source of current supply may be connected (one or both) through a Mercoid switch control generally designated 53, with a line represented by wires 54 and 55 from which leads 56, 57, 58, 59 and 61, all in parallel, are tapped respectively to the blower motor 27, the solenoid control 35 for the valve 11, the compressor motor 48, the solenoid control for the valve 38, and the intake damper solenoid control 19. The Mercoid control switch mechanism 53 which may be of any of several types well known on the market, may be arranged for control either through the pressure of steam generated within the boiler or in the line 37, or it may be arranged for thermostatic or temperature operation as will be understood. Its location is relatively immaterial except that it should reflect some characteristic of the steam in the boiler or the condition of the fire in the furnace, as will also be understood. The air tank 44 may also have a connection 62 leading to a rheostat or pressure actuated control switch 63 of any suitable character mounted on top of the compressor motor whereby to maintain a substantially constant pressure on the air in the air tank and flowing to the jets 43, and such switch may be arranged to reduce the speed of the motor 48 or to shut off the motor if the pressure in the air tank increases beyond a predetermined point.

In operation, as when starting a fire in the furnace under the boiler, the arrangement may be such that the valve 11, is in closed position over the end of duct 22 so that for the time being products of combustion flow up and out the chimney or stack 8. In this case the Mercoid control switch is open so that neither the motor 27 nor the motor 48 is in operation and the solenoids 19, 35 and 38 are deenergized and the valves controlled by the solenoids are in closed position. When a pre-determined temperature is attained in the boiler or a pre-deter-

mined pressure as for instance 1 lb. of steam is generated in the boiler, the Mercoid control switch may close thereby energizing all of the solenoids and opening the valves they control, while at the same time the motors 27 and 48 are started to operate the blower 26 and to furnish compressed air into the mixing chamber. With the valve 38 open steam is admitted into the header 39, and through each of the jets 41, into the products of combustion being drawn into ducts 22 and 23 and through the mixing chamber 24, duct 25 and blower 26 from which the mixture is blown through duct 28 to the draft intake of the furnace. During the initial period of operation a separate draft intake (not shown) may be opened, or if desired, a separate circuit may be provided for the blower and compressor motors 27 and 48, respectively, to supply sufficient air for the initial combustion period, but during such time the valve 11 will remain closed over the end of duct 22 and no steam will be supplied to the mixing chamber. With such an arrangement, automatic or manual control means may be provided for connecting and disconnecting the secondary circuit with and from the motors 27 and 48 when the steam pressure or temperature rises to the point where the control system of Fig. 3 comes into operation.

Assuming that the Mercoid control has been set to close the circuit when the steam pressure in the boiler reaches 1 lb. (gauge) or a temperature corresponding to such pressure if the switch operates thermostatically, a substantial amount of the smoke and other products of combustion will be deflected by the opening of valve 11 into the ducts 22 and 23 and drawn into mixing chamber 24 by the action of the blower 26. At the same time the opening of solenoid valve 38 admits steam into header 39 and the compressor 47 supplies compressed air into tank 44 and thence into the mixing chamber. The jets of compressed air and steam enter the mixing chamber and agitate or produce turbulence of the contents of the mixing chamber and tend to aid in accelerating the velocity of the mixture toward the blower. The turbulence or agitation produced within the mixing chamber practically insures complete mixing of the products of combustion with the air and steam before the mixture reaches the blower which of course may be considered as supplementing the mixing if any additional mixing or homogenizing is necessary. The mixture thus prepared is supplied to the furnace beneath the grates (some or all might also be delivered immediately over the fire within the furnace), with the result that substantially complete combustion of incompletely burned gases and smoke particles is effected.

After the steam pressure in the boiler or the temperature thereof has reached a predetermined point, as for instance, when the steam pressure reaches 2 pounds (gauge) which is a satisfactory maximum working pressure for ordinary house heating purposes under ordinary conditions, the furnace fire may be banked during which period there will be relatively little loss in unburned fuel products. Therefore, the Mercoid control is set to open the circuit to the motors 27 and 48 and to the solenoids 19, 38 and 35 at the desired pressure in the boiler or temperature thereof. Opening the circuit will close the valves 11 and 29 in the flue and intake duct and also will close the steam control valve 38. The operation of the fuel economizer and smoke eliminator then ceases until the steam

pressure or boiler temperature drops to a predetermined point, say 1 pound pressure (gauge) at which time the Mercoid control again closes the circuit and the cycle of operations previously described is repeated. Under some circumstances it may be desirable to set the Mercoid control to close the circuit when the furnace is being started in which case the valves 11, 29 and 38 open and remain open until some predetermined steam pressure or temperature has been attained in the boiler and at the same time the blower and compressor will be operating although until steam is actually formed in the boiler, no steam will be supplied to the mixing chamber. 15 When no steam is being supplied to the mixing chamber, the operation does not appear to be as satisfactory as when it is being supplied thereto. The admixture of steam with air to the combustible products exhausting from the furnace apparently has several effects. In the first place the injection of the steam and the fresh air in jet form produces a mechanical mixing or turbulence within the mixing chamber which, of course, tends to result in a thoroughly homogeneous mixture of oxygen and combustible particles and gases thereby enabling the particles and gases to be burned completely when reaching kindling temperature in the furnace. Second, the steam seems to act as an aid or catalyst 20 whereby the oxygen may contact the combustible particles and gases although at a temperature below the point of ignition or chemical combination therewith and also to associate itself in some way with the incompletely burned products 25 of combustion such, as, for instance, carbon monoxide with the result that upon the passage of the mixture to the zone of combustion in the furnace the combustible particles of the smoke, i. e. the carbon, and other combustible products, 30 such as carbon monoxide gas, are substantially completely consumed or oxidized. The steam may also tend to combine chemically with some of the hot products of combustion to form, by dissociation or otherwise, combustible gases. I 35 have found, for instance, that the mixture as it issues from the mixing chamber will burn freely with a blue flame when brought to kindling temperature, assuming that sufficient air to support combustion has been supplied to the mixture. 40 And a third effect seems to be of value, namely, the pre-heating of the air which is jetted into the mixing chamber. The pre-heating seems to have a materially beneficial effect 45 even beyond the effect of the retention and addition of so many B. t. u.'s, as the pre-heated air issues from the mixing chamber will burn freely with a blue flame when brought to kindling temperature, assuming that sufficient air to support combustion has been supplied to the mixture. 50 And a third effect seems to be of value, namely, the pre-heating of the air which is jetted into the mixing chamber. The pre-heating seems to have a materially beneficial effect even beyond the effect of the retention and addition of so many B. t. u.'s, as the pre-heated air 55 appears to mix the more readily and the more thoroughly and the more intimately with the combustion products including the gases and combustible particles flowing into the mixing chamber, than it does if not pre-heated.

I am unable to explain these actions, reactions and phenomena which appear to take place and on which I have attempted to theorize in this description, but I do know that remarkable results in fuel economizing and in smoke abatement have been attained on test with apparatuses constructed in accordance with this disclosure. Smoke is almost completely eliminated and a saving of 20 per cent or more in fuel, over ordinary firing, has been obtained.

While I have illustrated and described a preferred embodiment of the invention and the preferred method of operation, it will be appreciated that the invention is susceptible of various other embodiments and that other methods of

operation may be utilized without departing from the invention spirit and the scope of the appended claims.

I claim:

1. In an apparatus of the character described, means providing a mixing chamber, means including a plurality of nozzles for supplying steam and air under pressure into said mixing chamber for commingling with products of combustion contained in said chamber, said nozzles being arranged at spaced places circumferentially of the chamber, means for connecting said chamber with a furnace outlet, means for connecting said chamber with the draft inlet of a furnace, and means operative at a predetermined steam pressure for cutting off the supply of steam and air from said chamber.

2. In an apparatus of the character described, means providing a mixing chamber, means for supplying steam and air to said mixing chamber for commingling with products of combustion contained in said chamber, means for connecting said chamber with a furnace outlet, and means for connecting said chamber with the draft inlet of a furnace, valve means for opening and closing the connection between said chamber and draft inlet, and means operated by variations in boiler pressure during operation of the furnace for controlling the supply of air and steam to said chamber and simultaneously operating said valve means, said valve means being open when steam and air are being supplied to said chamber.

3. In an apparatus of the character described, means providing a mixing chamber, means for supplying steam and air to said mixing chamber for commingling with products of combustion contained in said chamber, means for connecting said chamber with a furnace outlet, means for connecting said chamber with the draft inlet of a furnace, blower means for feeding the mixture from said chamber into the draft inlet of the furnace, valve means for opening and closing the connection between said chamber and the said draft inlet, and means operative upon the attainment of a predetermined steam pressure for automatically cutting off the supply of steam and air to said chamber and for substantially simultaneously closing said valve.

4. In an apparatus of the character described, means providing a mixing chamber having an inlet and an outlet for exhaust stack products from a furnace, duct means for connecting the inlet of said chamber with the exhaust stack of a furnace, duct means for connecting the outlet of said chamber with the draft intake of a furnace, means including a plurality of nozzles for supplying steam and air to said chamber and from a plurality of places into said chamber whereby intimately to mix with exhaust products from the furnace, and means for pre-heating the air supplied to said chamber.

5. In an apparatus of the character described, means providing a mixing chamber having an inlet and an outlet for exhaust stack products from a furnace, duct means for connecting the inlet of said chamber with the exhaust stack of a furnace, duct means for connecting the outlet of said chamber with the draft intake of a furnace, means including a plurality of nozzles for supplying steam and air to said chamber and said nozzles delivering steam and air into said chamber from a plurality of places longitudinally and circumferentially of said chamber whereby intimately to mix with exhaust products

from the furnace, and means for pre-heating the air supplied to said chamber.

6. In an apparatus of the character described, means providing a mixing chamber having an inlet and an outlet for exhaust stack products from a furnace, duct means for connecting the inlet of said chamber with the exhaust stack of a furnace, duct means for connecting the outlet of said chamber with the draft intake of a furnace, and means including a plurality of nozzles for supplying steam and air to said chamber and said nozzles being arranged and disposed to deliver air and steam into said chamber from a plurality of places longitudinally and circumferentially of said chamber whereby intimately to mix with exhaust products from the furnace.

7. In an apparatus of the character described, means providing a mixing chamber having an inlet and an outlet for exhaust stack products from a furnace, duct means for connecting the inlet of said chamber with the exhaust stack of a furnace, duct means for connecting the outlet of said chamber with the draft intake of a furnace, means including a plurality of nozzles for supplying steam and air under pressure to said chamber and from a plurality of places longitudinally and circumferentially of said chamber whereby intimately to mix with exhaust products from the furnace, means for shutting-off the steam supply to said nozzles, and means automatically operative to close said duct means to said draft intake substantially simultaneously with operation of said steam supply shut-off means.

8. In an apparatus of the character described, a duct for connecting the exhaust stack of a furnace with the draft inlet thereof, means for deflecting exhaust products from said stack into said duct, means for supplying air and steam into said duct for mixing with products of combustion therein, means for causing a forced flow through said duct to said draft inlet, means for opening and closing said duct to said draft inlet, and means automatically operative to render said deflecting means inoperative to deflect exhaust products into said duct upon the closing of said duct to said draft inlet and, substantially simultaneously, to effect cessation of operation of said means for causing a forced flow through said duct.

9. In an apparatus of the character described, means providing a mixing chamber having an inlet and outlet, duct means for connecting the inlet of said chamber with the exhaust stack of a furnace, electric motor operated means for deflecting exhaust products from said stack toward said chamber, duct means for connecting the outlet of said chamber with the draft inlet of a furnace, electric motor operated means for causing a forced flow of exhaust products from said stack to said draft intake through said duct means and chamber, electric motor operated means for supplying compressed air into said chamber and into the exhaust products passing through said chamber, electric motor operated valve means for closing said duct means to said draft inlet, means for cutting off the supply of compressed air, and means for closing said valve means.

10. In an apparatus of the character described, means providing a mixing chamber having an inlet and outlet, duct means for connecting the inlet of said chamber with the exhaust stack of a furnace, means for deflecting exhaust prod-

ucts from said stack toward said chamber, duct means for connecting the outlet of said chamber with the draft inlet of a furnace, means for causing a forced flow of exhaust products from said stack to said draft intake through said duct means and chamber, means for supplying preheated air and steam into said chamber and into the exhaust products passing through said chamber, valve means for closing said duct means to said draft inlet, means for stopping the supply of air and steam to said chamber, and means automatically operative to close said valve means upon cessation of the supply of steam and air to said chamber.

11. In an apparatus of the character described, means providing a mixing chamber having an inlet and outlet, duct means for connecting the inlet of said chamber with the exhaust stack of a furnace, motor operated means for deflecting

5 exhaust products from said stack toward said chamber, duct means for connecting the outlet of said chamber with the draft inlet of a furnace, motor driven means for causing a forced flow of exhaust products from said stack to said draft intake through said duct means and chamber, means for supplying preheated air into said chamber and into the exhaust products passing through said chamber, motor controlled means for supplying steam to the products in said chamber, motor operated valve means for closing said duct means to said draft inlet, and control means operative upon a predetermined rise in steam pressure for stopping the supply of air and steam to said chamber, for rendering said deflecting means inoperative and for automatically closing said valve means.

GEORGE J. BYRNE.
